CLAMP SCREW AND NUT FOR A TUCKING KNIFE

Abraham Gellman, New York, N. Y.

Application February 4, 1937, Serial No. 123,966

3 Claims. (Cl. 85—5)

This invention relates to new and useful improvements in a clamp screw and nut for holding the arms of a tucking knife in adjusted position.

The invention has for an object the construction of a knife as mentioned which is characterized by the fact that it has an arm adapted to be pivotally mounted and a blade with a straight edge over which the material to be tucked may be folded, and said blade being connected with the arm in a novel and advantageous manner.

More specifically, the invention contemplates connecting the blade and arm with each other by the use of a groove and tongue arrangement and providing a single clamp screw which may be opened to loosen the blade and arm so that they may be adjusted, or which may be closed.

Still further the invention proposes an arrangement by which the clamp screw is made of several sections and arranged so that the head portion thereof may be released when desired to eliminate the necessity of opening the screw. Thus, additional convenience is provided for adjusting the tucking knife.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a plan view of a sewing machine equipped with a tucking knife according to this invention.

Fig. 2 is a plan view of the tucking knife per se. Fig. 3 is an edge elevational view of Fig. 2.

Fig. 4 is a bottom view of Fig. 2.

Fig. 5 is a transverse sectional view taken on the line 5—5 of Fig. 2.

Fig. 6 is a view similar to Fig. 5 but illustrating a modification of the invention.

The tucking knife, according to this invention, comprises an arm 10 adapted to be pivotally mounted at the point 11 on the table 12 of a sewing machine 13. This arm is associated with a blade 14 having a straight edge 14^a and also having a stem portion 14^b slidable in a groove 10^a in the arm 10. A clamp screw 15 is associated with the stem and arm for holding these parts in relatively adjusted positions.

The full line position of the tucking knife, shown in Fig. 1, is the operative position in which cloth material, indicated by the dot and dash line 16 may be folded over the edge of the tucking knife and fed to the sewing machine. The dot

and dash lines indicate a moved position of the tucking knife in which it is inoperative.

The arm 10 is formed with an aperture 11^a through which the pivot element 11 passes to pivotally mount the arm upon a sewing machine table. The blade 14 has its outer extremity 14^c bent downwards to engage the top face of the sewing machine table so that the goods which is being operated upon will merely slide over the tucking knife. The opposite edge of the blade 14 is formed with a projecting finger portion 14^d adjacent a hollowed area 14^e. These parts are arranged so that the material which is being tucked, is guided to a close position to the operating needle of the sewing machine.

The stem portion 14^b is formed with a slot 17 through which the clamp screw passes. The groove 10^a is formed by merely recessing a groove into the top face of the arm 10. At the area where the groove is formed the arm 10 has a widened portion 10^c. This widened portion is imprinted or inscribed in any other manner with a scale 18. A line 19 is formed upon the stem 14^b and cooperates with the scale to indicate the positions of the blade 14.

The clamp screw 15 has a large and flat head 15^a. It has a screw portion 15^b extending through the slot 17 and through an opening 20 in the arm 10. A nut 15^c threadedly engages on the screw portion 15^b. A friction washer 15^d is interposed between the nut 15^c and the bottom face of the arm 10.

To adjust the blade 14 it is merely necessary to pivot it to an inoperative position as shown in Fig. 1 and then to turn the nut 15^c to loosen the clamp screw. The blade and arm may then be relatively adjusted as required. The nut 15^c is then tightened.

In Fig. 6 a modification of the invention has been disclosed which distinguishes from the prior form in the fact that the head of the clamp screw may be loosened to release the blade, in addition to the fact that the nut may be loosened for the same purpose. There is therefore a choice for loosening the parts.

More specifically, according to this form of the invention, the clamp screw has a head portion 25 formed with a recess 26 into which a headed shank 27 engages. A resilient washer 28 is interposed between the base of the recess 26 and the head of the shank 27. Several pins 29 are mounted in the head 25 and extend into the recess 26 and engage against a shoulder 27^a of the headed shank 27. This shoulder is formed with cam cutouts 30 arranged so that in a certain posi-

tion of the head 25 the pins 29 are aligned with the cutouts and then the head 25 is loose, and in another position the pins 29 straddle the cutouts 30 and engage beneath the shoulder 27^a and then 5 the head 25 is tight. The shank 27 passes through the slot 17 in the stem 14^b. It also passes through the opening 20 in the arm 10 and threadedly engages the nut 15^c. There is also a friction washer 15^d between the nut and the arm. The top face 10 of the nut 25 is formed with a hollow portion 25^a adapted to receive a thumb.

As shown in Fig. 6 the parts are clamped together. When required the head 25 may be slightly forced downwards against the action of 15 the resilient element 26 and then the head 25 turned to align the pins 29 with the cutouts 30. The blade 14 and arm 10 are then loose and may be adjusted. They may be re-tightened by turning the head 25 to cause the pins 29 to ride beneath the shoulder 27^a. The blade and arm may 20 also be loosened by operating the nut 15^c.

While I have illustrated and described the preferred embodiments of my invention, it is to be understood that I do not limit myself to the 25 precise constructions herein disclosed and the right is reserved to all changes and modifications coming within the scope of the invention as defined in the appended claims.

Having thus described my invention, what I 30 claim as new, and desire to secure by United States Letters Patent is:—

1. In a device of the class described a clamp screw and nut for holding the arms of a tucking knife in adjusted positions, comprising a headed 35 shank portion and a head portion, the head of the shank portion engaging into a recess in said head portion, pins on the head portion engaging

against a shoulder formed by the bottom face of the head on said headed shank, said shoulder having cam cutouts formed radially therein and into which said pins may engage for releasing said head portion, and a resilient element interposed between the base of said recess and the head of the shank. 5

2. In a device of the class described a clamp screw and nut for holding the arms of a tucking knife in adjusted positions, comprising a headed shank portion and a head portion, the head of the shank portion engaging into a recess in said head portion, pins on the head portion engaging against a shoulder formed by the bottom face of the head on said headed shank, said shoulder 10 having cam cutouts formed radially therein and into which said pins may engage for releasing said head portion, and a resilient element interposed between the base of said recess and the head of the shank, the outer face of the head portion being recessed. 15

3. In a device of the class described a clamp screw and nut for holding the arms of a tucking knife in adjusted positions, comprising a headed shank portion and a head portion, the head of the shank portion engaging into a recess in said head portion, pins on the head portion engaging against a shoulder formed by the bottom face of the head on said headed shank, said shoulder 20 having cam cutouts formed radially therein and 30 into which said pins may engage for releasing said head portion, and a resilient element interposed between the base of said recess and the head of the shank, said resilient element comprising a rubber disc. 25
